Primary Examiner—James Gandy*Assistant Examiner*—Cathron B. Matta*Attorney, Agent, or Firm*—Harry M. Cross, Jr.[57] **CLAIM**

The ornamental design of a bottle carrier with finger grips, as shown and described.

DESCRIPTION

FIG. 1 is a top plan view of my new design for a bottle carrier with finger grips with the finger grips shown in the closed position, the opposite side being a mirror image thereof; and,

FIG. 2 is a perspective view of my new design at a reduced scale with the finger grips shown in the open position.
